US00D793252S

(12) **United States Design Patent** (10) Patent No.: **US D793,252 S**
 Prince (45) Date of Patent: ** Aug. 1, 2017

(54) **TRAY FOR JUGS**(71) Applicant: **Parmalat Canada Inc.**, Etobicoke (CA)(72) Inventor: **Sidney Scott Prince**, Hamilton (CA)(73) Assignee: **Parmalat Canada Inc.**, Etobicoke (CA)(***) Term: **15 Years**(21) Appl. No.: **29/550,868**(22) Filed: **Jan. 7, 2016****Related U.S. Application Data**

(62) Division of application No. 29/488,082, filed on Apr. 15, 2014, now Pat. No. Des. 750,975.

(30) **Foreign Application Priority Data**Oct. 15, 2013 (CA) 153482
Feb. 20, 2014 (CA) ..... 155233(51) **LOC (10) Cl.** ..... **09-03**(52) **U.S. Cl.**USPC ..... **D9/755**(58) **Field of Classification Search**

USPC D9/762, 757, 737, 761, 420-426, 432, D9/418, 415, 501, 72, 739, 742, 753, 756, D9/741; D7/611, 550.1, 605, 701, 553.1, D7/553.2, 614; D3/313, 304, 311, 314, D3/315; D6/396, 397, 449, 450, 466, D6/469, 629; D24/227; 206/139, 206/201-203, 427, 265, 504, 518, 519, 206/524.1, 557, 561, 564, 565, 703, 704, 206/705, 523, 586, 515, 521.1, 521.15, 206/521.3, 521.6, 521.8, 521.4, 521.9, 206/406; 220/4.26, 508; 229/406; 426/119, 112, 298, 614; D11/143, 155, D11/156

(57) **CLAIM**

The ornamental design for a tray for jugs, as shown and described.

DESCRIPTION

FIG. 1 is a top, front, right perspective view of a tray for jugs showing my new design;
FIG. 2 is a bottom, front, left perspective view thereof;
FIG. 3 is a right side view thereof;
FIG. 4 is a left side view thereof;
FIG. 5 is a front side view thereof;
FIG. 6 is a rear side view thereof;
FIG. 7 is a cross-sectional view at 7-7 in FIG. 1 thereof;
FIG. 8 is a top view thereof; and,
FIG. 9 is a bottom view thereof.

1 Claim, 6 Drawing Sheets
